TELEVISION PICK-UP TUBES

Richard Theile, Cambridge, England, assignor to Pye Limited, Cambridge, England, a British company

Application May 5, 1952, Serial No. 286,069

Claims priority, application Great Britain May 9, 1951

5 Claims. (Cl. 315—11)

The present invention relates to television pick-up tubes of the storage type in which the scanning of the storage surface or target is effected by high-velocity electrons, for example of the order of 1000 volts. Tubes of this type include those known as iconoscopes and image-iconoscopes.

Various proposals have previously been made to incorporate secondary-electron multipliers within the pick-up tube for improving its sensitivity. Hitherto, however, satisfactory results from the use of secondary-electron multipliers in pick-up tubes with high-velocity scanning have not been commercially achieved, and secondary-electron multiplication is only incorporated in pick-up tubes with low-velocity electron scanning (for example image-orthicon tubes), as in such tubes the signal current from all parts of the storage plate returns substantially to the electron gun where it can be easily collected and directed into the multiplier.

The difficulty in obtaining satisfactory secondary-electron multiplication in high-velocity-scanned tubes is caused by the fact that the signal current consists of low-velocity secondary electrons which are released with different initial velocities and different directions of emission at different parts of the storage plate and are collected by the collector electrode, usually in the form of a conducting wall coating inside the tube envelope and surrounding the storage plate.

The present invention has for its object to provide an arrangement which reduces or overcomes the difficulties in collecting and accelerating the signal electrons from all parts of the storage plate of a high-velocity-scanned tube, and thereby enabling efficient secondary-electron multiplication to be obtained. For achieving the results according to the invention two problems have to be solved, namely (1) collection of the secondary electrons into the multiplier must be substantially uniform over the whole surface of the storage plate, and (2) the potential at which the surface of the storage plate stabilises must only be effected to a small extent by the potential of the first multiplier electrode (dynode) since it is essential to maintain a sufficient potential difference (of the order of 100 volts or more) between the surface of the storage plate and the first dynode in order to obtain the necessary acceleration of the collected secondary electrons for producing a high secondary-emission ratio in the multiplier system.

According to the present invention, the multiplier is constructed in one or more sections extending around the front of the storage plate surface, the multiplier electrodes being screened from the storage plate by a screen or screens maintained at a potential which is substantially less (of the order of a hundred volts or more) than the potential of the first multiplier dynode, and preferably at a potential which is approximately the same as the potential of the internal wall coating of the tube, the screening action of a screen being such as to reduce the penetration of the positive field of the associated first multiplier dynode to such a small value that the storage

2

surface stabilises at a potential which is positive with respect to the wall coating or other adjacent electrodes but is low with respect to the potential of said first dynode, whilst permitting a sufficiently high field penetration to effect collection of substantially all the secondary electrons released from the storage surface by the multiplier. As the mean velocity of the released secondary electrons is generally of the order of 2 to 3 volts and the optimum dynode potential is approximately 100 or more volts, a field penetration of less than 10%, for example about 3%, provides a suitable compromise, that is to say, that in the triode system consisting of the storage plate, the screen and the dynode, about 3% of the positive field of the dynode should be present at the surface of the storage plate.

In a preferred embodiment, in which an electron multiplier is utilised in conjunction with an image-converter tube, for example an image iconoscope, the photo-cathode of the tube is arranged to be operative only during the 20 picture-blanking intervals (frame-blanking intervals and line-blanking intervals) when the tube is operating under high level light conditions, so that the photo-current is interrupted during the actual scanning of the tube. This 25 enables the noise level to be reduced under such high-level light conditions.

In order that the invention may be more fully understood, reference will now be made to the accompanying drawing, in which:

Fig. 1 shows a pick-up tube of the image-iconoscope type constructed according to the invention,

Fig. 2 shows a detail view of a modification.

The pick-up tube shown in Fig. 1 is of the image-iconoscope type, and comprises an evacuated envelope 1 formed in known manner at one end with a photo-cathode 2 on which the picture to be projected is focussed by a lens 3. The released photo-electrons are focussed by the focus coil 4 onto the storage plate 5 backed by the signal plate 6, the focus coil 4 being energised from a suitable potential source 19. The storage plate is arranged to be scanned by an electron gun 7 fed from source 20 and located in a side tube of the envelope 1, the scanning beam being focussed and deflected by the focus coil 8 energised from potential source 21 and deflecting coils 9 fed with modulating waveforms from source 22. The internal surface of the envelope 1 is provided with a conductive wall coating 10 normally constituting the collector electrode of the tube. The tube construction as so far described is conventional and well-known in the art.

According to the present invention, the tube also includes an electron multiplier which may be in the form of a ring structure generally indicated at 11, the axis of which is slightly offset from the tube axis, as shown, in order to minimise masking of electrons emanating from gun 7. However in certain circumstances it may be co-axially mounted if desired. The multiplier electrodes constituted by the first, second, third and fourth dynodes 12, 13, 14 and 15 respectively and the collector 16 are enclosed in a screening box 17, the end of which 50 facing the storage plate 5 is covered by a screening mesh 18 through which the secondary electrons released from the storage plate 5 pass to impinge upon the first dynode 12. The screening box 17 and mesh 18 may be held at approximately the same potential as the wall coating 10 and are held at a potential substantially less (of the order of a hundred volts or more) than the potential of the first dynode 12, as shown schematically by the interposition of potential source 23. The size of the aperture in the screening mesh 18 and its spacing from the first 55 dynode 12 are so determined that there is about 3% penetration of the positive field of the first dynode into the space near the storage plate. Such a low field,

penetration does not substantially increase the potential at which the surface of the storage plate stabilises, whilst it is sufficient to accelerate and cause the secondary electrons to be collected by the multiplier. The field penetration should, furthermore, be such that the potential at which the surface of the storage plate stabilises is positive with respect to the wall coating so that the latter produces a retarding field to the secondary electrons and the latter are not lost to the surrounding electrodes but are collected by the multiplier.

According to a feature of the invention, the ratio of the diameter of the annular multiplier structure to the distance between the screening mesh and the storage plate is made such as to produce a substantially uniform field over the surface of the storage plate. Since the insulating surface of the storage plate stabilises approximately to the adjacent space potential, any non-uniformity in the space potential produced by the field from the multiplier dynode would cause different portions of the storage plate to stabilise at different potentials, thereby giving rise to spurious signals. The ratio of the said diameter and distance is so chosen that the storage plate is at a position where the field is of maximum flatness, the influence exerted by the signal plate and the wall coating on this field being taken into account.

The distance between the first dynode and the screening mesh, as well as the relative potentials therebetween, have an effect upon this field. Further, by varying the relative potentials of the screening box and the wall coating, for example by making the potential of the former slightly positive or negative with respect to the potential of the latter, shown schematically by interposition of the source 24, which makes the potential of the screening box slightly positive with respect to the coating 10, slight correction may be effected in the field disposition in order to obtain field uniformity over the surface of the storage plate.

If desired, the geometry of the arrangement or the potentials applied to different parts thereof may be adjusted to produce a desired non-uniform field over the storage plate to compensate for "shading" or other spurious signals.

According to a further feature of the invention, the surface of the storage plate 5 is constructed to possess a small amount of surface leakage in order to equalise any residual unevenness of the surface potential of the storage plate without noticeable dilution of the charge pattern due to the picture storage. This may be achieved by providing the surface of the storage plate with a slightly conducting layer 25, which may, for instance be made of glass. An insulating layer 26 is interposed between the conducting layer 25 and the surface 5. The peripheral regions of the storage surface may be formed with conducting electrodes 27 which, if desired, may be connected to a source 28 of bias for biasing the surface of the storage plate. Preferably, the source 28 is adjustable under control of control member 29.

With a pick-up tube such as so far described above, the noise level in the picture is produced by the shot noise of the scanning beam current and also of the photo-current itself. When operating under low-light conditions for which the multiplier tube is most suitable, the average photo-current is less than or at the most equal to, the scanning-beam current, so that the noise due to the photo-current is not appreciable and only increases the general noise by a few percent. However, under high-light intensities the lens adjustment (aperture) of the pick-up tube is more critical in order to avoid noise, as the increased light, which improves the picture, causes excessive noise.

Another feature of the invention has for its object to overcome or reduce this difficulty and to this end the tube is arranged to have its photo-cathode 2 operative

only during the picture blanking intervals which may be the frame blanking intervals and/or the line blanking intervals when the tube is operating under high-light conditions so that the photo-current is interrupted during the actual scanning of the tube.

To bring this about, the photo-cathode 2 may be biased negatively by a series of pulses corresponding to the picture-blanking pulses. In the embodiment illustrated, the biasing pulses are produced by a pulsing device 30 although, if desired, they may be obtained by appropriate voltage amplification of the blanking pulses. A switch 31 may be incorporated to cut out the biasing pulses and to bias the photo-cathode 2 continuously for continuous photo-emission when the tube is operating under low-light conditions. The pulsing device 30 is connected to a suitable source 32 for the production of the negative pulses. If desired, means may be provided for operating the switch 31 automatically in dependence upon the amount of available light in the scene or picture to be transmitted.

Whilst a particular embodiment has been described, it will be understood that various modifications may be made without departing from the scope of the invention. Thus, for example, the screen associated with the first dynode need not be in the form of a mesh as shown at 18 in Fig. 1 but may be constructed from sheet material with one or more apertures or slots therein. Such a modification is illustrated in Figure 2, which shows only a part of the complete tube, the screening box 17a having its front wall formed of sheet material provided with an annular slot 18a facing the storage plate 5. The first dynode 12a is arranged within the screening box and the secondary electrons released therefrom are collected by the collector 16a positioned within the front section of the box and screened from the aperture 18a thereof by the flange portions 18b, so that the collector 16a has no influence on the collection of the secondary electrons released from the surface of the storage plate.

Furthermore, the multiplier structure need not be in the form of a circular ring but can be of any other convenient shape, for example of rectangular form corresponding approximately to the shape of the picture on the storage plate. The multiplier may be constructed as a single unit or from a plurality of separate sections which may be spaced apart; for example it may comprise four straight sections assembled to form a rectangular multiplier structure, the ends of the sections preferably being close together.

I claim:

1. In television transmitting apparatus, the combination of a pick-up tube of the charge-storage type having a charge-storage target with means for scanning said target with a beam of high-velocity electrons, a secondary-electron multiplier device located between said target and said scanning means and out of the path of the scanning beam and comprising at least one dynode and a collector electrode arranged in an enclosed hollow structure surrounding the scanning beam, an electron-permeable electrode between said multiplier device and said target, and means for applying potentials to said multiplier device and to said electron-permeable electrode for producing a field-penetration ratio of the adjacent dynode of said multiplier device through said electron-permeable electrode to said charge-storage target which is less than 10%.
2. A television pick-up tube of the storage type in which the scanning of the charge-storage target is effected by high-velocity electrons, comprising a secondary-electron multiplier located between said target and the source of scanning electrons, said multiplier device comprising at least one dynode and a collector electrode totally enclosed within an enclosed hollow structure facing said target, the face of said structure confronting said charge-storage target comprising a mesh electrode.
3. A television pick-up tube of the storage type in which the scanning of the charge-storage target is effected

by high-velocity electrons, comprising an electron multiplier consisting of at least one dynode and a collector electrode totally enclosed within an annular enclosed hollow structure facing and closely adjacent said target, the wall of said structure confronting said charge-storage surface comprising an annular mesh electrode.

4. A television pick-up tube comprising an envelope, a charge-storage surface within said envelope at one end thereof, a tubular member projecting from said envelope at an acute angle and communicating with the interior of said envelope and pointing towards said charge-storage surface, a source of electrons in said tubular member for producing a beam of electrons for scanning said charge-storage surface, and an electron multiplier consisting of at least one dynode and a collector electrode enclosed within an annular enclosed hollow structure facing said target and whose axis is off-set with respect to the longitudinal axis of the envelope and located out of the path of said beam of scanning electrons, the wall of said enclosed hollow structure confronting said target comprising an annular mesh electrode.

5. Apparatus for transmitting television signals, comprising a television pick-up tube comprising an envelope, a charge-storage surface within said envelope at one end thereof, a tubular member projecting from said envelope at an acute angle and communicating with the interior

of said envelope and pointing towards said charge-storage surface, a source of electrons in said tubular member for producing a beam of electrons for scanning said charge-storage surface, an electron multiplier consisting of at least one dynode and a collector electrode enclosed within an annular enclosed hollow structure facing said target and whose axis is off-set with respect to the longitudinal axis of the envelope and located out of the path of said beam of scanning electrons, the wall of said enclosed hollow structure confronting said target comprising an annular mesh electrode, a photo-cathode in said envelope at the end thereof opposite said charge-storage surface, and means for blanking out said photo-cathode during the time that the scanning beam is scanning said charge-storage surface.
